UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed May 23, 1923. Serial No. 640,870.

My invention relates to that class of locks more commonly known as pin tumbler locks, and an object of my invention, among others, is the construction of a lock of this 5 class, whereby the chance of operating it without a key, or without a key especially designed for it, shall be reduced to a minimum; and a further object of the invention, is to provide a lock of this class that shall 10 not require extreme care and precision in its construction.

One form of a lock embodying my invention, and in the construction and use of which the objects herein set out, as well 15 as others, may be attained, is illustrated in the accompanying drawings, in which—

Figure 1 is a view in cross section through the cylinder and plug or barrel of my improved lock on a plane passing through one 20 of the tumbler sockets, the tumbler being shown in full.

Figure 2 is a side view of the cylinder partially broken away in central lengthwise section.

25 Figure 3 is a side view of the key for operating the lock.

Figure 4 is a view, scale enlarged, in cross section through a fragment of the lock cylinder and plug illustrating its operation.

30 Figure 5 is a similar view further illustrating the operation of the lock member.

Figure 6 is a view on a plane passing centrally lengthwise through the plug, a 35 fragment of which together with the cylinder is shown, and illustrating the position of the tumblers to permit rotation of the plug.

Heretofore, in the construction of locks 40 of this class, great care and precision have been required, as well as much care and skill to assemble the parts, to avoid looseness, and especially after some wear, to an extent to cause the parts to stick in operation, and it 45 is to avoid these objections that I have devised a lock embodying my invention illustrated and described herein. Such lock comprises a plug or barrel 7 fitted within a cylinder 8, said plug having a slot 9 for the reception of a key 10, an actuator 11 being secured to the end of the plug projecting from the cylinder for the purpose of actuating a lock or other member in a 50 manner that will be readily understood, all

of the parts thus far described being of old 55 and well-known construction. Tumbler sockets 12 are formed in the plug, and a tumbler case 13 projects from the cylinder and is provided with tumbler sockets 14, a set of tumblers being located in the sockets 60 in the plug, and another set of tumblers being located in the sockets in said case, in a manner common to prior devices of this kind.

When the tumblers are in their normal positions, as shown in Figure 2 the outer set of tumblers project into the sockets in the plug or barrel and thereby prevent the plug from being turned. When the key 10 is inserted, the notches 15 therein in which 65 the tumblers of the lower set rest, will so position the tumblers that the lines of separation between each set of tumblers will be coincident with the line of separation between the outer surface of the plug and the 70 inner surface of the cylinder.

A lock made as above described and having tumblers of ordinary construction with the ends thereof square with the axis, if made so that they are somewhat loose in 80 their sockets will permit a slight rotatable play of the plug so that the sockets common to each pair of tumblers in the plug and in the tumbler case will not register, but will present a shoulder at the entrance of the 85 socket in the plug on one side and at the entrance of the socket in the tumbler case on the opposite side in the path of movement of the tumblers, and as shown in Fig. 4 of the drawings, that will either cause the 90 tumblers to stick or that will prevent their movement. If the plug be constructed loose enough to permit a little endwise play the same conditions will arise as just above described, except that the shoulders in the 95 tumbler sockets will be located at right angles to the positions above described.

In either event the movement of the key into its slot is either rendered difficult or is prevented, and therefore it has been essential, prior to my invention, that the parts of the lock shall be made with precision and accuracy.

In order to avoid these requirements for accuracy and precision in construction of 105 parts and in the assembly of such parts, I provide the tumblers 16 with rounded corners 17 that, when there is a certain per-

mitted looseness between the parts of the lock, will come in contact with shoulders 18-19 hereinabove referred to and will permit the tumblers to slip past the corners and into the sockets 14 in the case 13 as the higher portions of the key raise the tumblers above the positions occupied by them when the key is fully inserted and the tumblers rest on the bottoms of the notches in the key. The key is thus permitted easy and ready entry into the key slot, even though a certain permissive looseness is present in the fit between the lock members.

In order that the tumblers thus formed and having a loose fit, as above described, shall not permit rotation of the plug by the operation of a key not intended for the lock, a guard 20, in the form of a projection from the end of each of the tumblers of the lower set, is provided, the outer ends of these guards being rounded, preferably on a radius slightly less than the radius of the key plug, and the undersides of these guards are undercut as shown especially in Figures 4 and 5 of the drawings, providing acute angular corners 21. Guards 22 are also provided on the upper set of tumblers, of the same construction as those just described as to the lower tumblers.

If an attempt be made to operate the lock by a key having shallower notches than those on the key intended for the lock, the guards 20 on the lower set of tumblers will project into the tumbler sockets 14 in the case 13, and when the plug is rotated to a slight extent by this key said guards will be carried against the walls of the sockets 14 and this will prevent further rotation of the plug. Further than this the tumblers will be tipped, as shown in Fig. 4, so that the corners of the shoulders 18 will project into the recesses formed by the beveled under surfaces of the guards and thus tend to draw the guards further into such sockets, and this increases the efficiency of the guards in this respect.

If a key having notches deeper than those of the key intended for operation of the lock be employed, the tumblers of the upper set will rest below their proper levels and the guards 22 will be located in the sockets 12 in the plug, and the same effect as just described with respect to the lower tumblers will be obtained by the action of the upper set of tumblers.

When an attempt is made to "pick" a lock by means of a wire inserted in the key slot of a lock of the prior art to raise the tumblers to their proper positions, force is applied to the plug, as by an instrument inserted in the key slot, and it is rotated slightly until stopped by one of the tumblers of the upper set. One of the tumblers only will do this, as it is practically impossible to make the lock so that more than one

of the tumblers will act in this way. A wire is inserted and by "feeling" the binding tumbler is located. Pressure on the plug is now slightly released just enough to permit the binding tumbler to be raised, and when it reaches its proper position, a slight further rotation of the plug will take place until stopped by the next tumbler, the lower end of the tumbler first raised now resting on the edge of the plug projecting slightly underneath the sockets 14. The wire is removed from engagement with said tumbler that is now held as described, and the same operation is repeated with the second tumbler found to bind, and so on until all the tumblers have been properly located when the plug may be turned.

If this operation be attempted in my improved lock, the binding tumbler of the upper set may be located and raised, as above described, but this binding action will cease before the tumbler is raised to its proper position, owing to the presence of the guard that is smaller in diameter than the body of the tumbler. The element of "feeling out" is therefore removed before the tumblers are raised to their positions to permit rotation of the plug, at the time of removal of this "feeling out" element the guard on a tumbler in one plug or cylinder member projecting into a socket in the other plug or cylinder member and thus preventing further rotation of the plug.

In order to further increase the resistance to movement of the plug and thereby increase the difficulty of surreptitious operation of the parts, the walls of the sockets 14 and 12 are roughened, as at 23, and this will so increase the friction that engagement of the guards with the roughened surface will increase to a material extent the movement of the tumblers, when such movement is attempted by means other than the key design for the lock in which the tumblers are located.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A pin tumbler comprising a body having a relieved corner at that end to be located at the plane of separation between the plug and cylinder to promote ease of movement of said tumbler into its socket, and a guard extending from the end of said body and smaller in diameter than said body.
2. A pin tumbler comprising a body hav-

- ing a relieved corner at that end to be located at the plane of separation between the plug and cylinder, and a guard smaller in diameter than said body and extending from 5 the end thereof and having a rounded end.
3. A pin tumbler comprising a body having a relieved corner at that end to be located at the plane of separation between the plug and cylinder, and a guard smaller in 10 diameter than said body and extending from the end of said body and having an undercut side wall.
4. A pin tumbler comprising a body having a relieved corner at that end to be located at the plane of separation between the plug and cylinder, and a guard extending from the end of said body and having an undercut side wall.
5. A lock comprising a cylinder, a plug 20 located in said cylinder, pin tumblers located in said plug, a pin tumbler located in a socket in said cylinder and comprising a body having a relieved corner at that end at the mouth of said socket, and a guard 25 projecting from said body and smaller in diameter than said body.
6. A lock comprising a cylinder, a plug located in said cylinder, a pin tumbler lo-
- cated in said plug, a pin tumbler located in said cylinder, said tumblers fitting loosely 30 within the plug and cylinder to allow a slight permissive tipping movement thereof, each of said pin tumblers having a body with a relieved corner at that end appurtenant to the other tumbler to promote ease of 35 movement of said tumbler into its socket, and a guard projecting from that end of each tumbler having a relieved corner.
7. A lock comprising a cylinder, a plug 40 located in said cylinder, a pin tumbler located in said plug, a pin tumbler located in said cylinder, each of said tumblers having a body with a relieved corner at that end appurtenant to the other tumbler, and a guard projecting from that end of each 45 tumbler having a relieved corner, said guards each being smaller in diameter than said body and having an undercut wall.
8. A lock comprising a pin tumbler element, and a member having a socket element 50 for movement thereinto of said pin tumbler element, one of said elements having a relieved corner to permit movement of said tumbler when out of line with said socket.

ELMER B. STONE.
